CLAIM

The ornamental design for a microdermabrasion paddle, as shown and described.

DESCRIPTION

FIG. 1 is a front perspective view of the microdermabrasion paddle showing my new design;

FIG. 2 is a back perspective view of FIG. 1;

FIG. 3 is a front elevational view of FIG. 1;

FIG. 4 is a back elevational view of FIG. 3;

FIG. 5 is a right-side elevational view of FIG. 3;

FIG. 6 is a left-side elevational view of FIG. 3;

FIG. 7 is a top plan view of FIG. 3;

FIG. 8 is a bottom plan view of FIG. 3;

FIG. 9 is the same view of the device in FIG. 4 now integrated with an abrasive surface;

FIG. 10 is a perspective view of the device of FIG. 1 integrated with a connector and handle showing one intended use;

FIG. 11 is an exploded view of the device in FIG. 10;

FIG. 12 is a perspective view of the device of FIG. 1 integrated with a connector and motorized vibration device showing another intended use; and,

FIG. 13 is an exploded view of the device in FIG. 12.

The broken lines shown in FIGS. 1-13 illustrate portions of the microdermabrasion paddle that form no part of the claimed design.

The additional broken lines in FIGS. 10-13 depict the connector and vibration devices, which illustrates environment and form no part of the claimed design.

1 Claim, 13 Drawing Sheets
